UNITED STATES PATENT OFFICE.

EDWIN S. GAYLORD, OF HARTFORD, CONNECTICUT.

IMPROVEMENT IN MICA CHIMNEYS FOR LAMPS.

Specification forming part of Letters Patent No. 35,675, dated June 24, 1862.

To all whom it may concern:

Be it known that I, EDWIN S. GAYLORD, of Hartford, county of Hartford and State of Connecticut, have invented a certain new and useful Improvement in Lamp-Chimneys; and I do hereby declare that the same is described and represented in the following specification and drawings.

To enable others skilled in the art to make and use the invention, I will proceed to describe its construction and advantage, referring to the drawings, in which the same letters indicate like parts in each of the figures.

The nature of this improvement in lamp-chimneys consists in the use or application of mica, in combination with form and compression rings at the top and bottom thereof, and a lateral joint-bar made single or in the form of a double-S clasp to hold or cover the edge of the mica, the object of which is to produce a cheaper and a more indestructible article of use and trade.

In the accompanying drawings, Figure 1 is an elevation showing the outside of the double-S clasp (or lock-joint) extending nearly or quite the whole length of the chimney, and the upper and lower outside compression-rings. Fig. 2 is a section cut lengthwise of the chimney, showing the mica compressed between the inner and outer rings both at the top and bottom. Fig. 3 is a cross section showing the edges of the mica compressed between the lap edges of the double-S-shaped clasp (or lock-joint.) I propose some times to dispense with the double-S clasp and substitute therefor a plain joint-plate to cover the outside of the joint.

d shows the mica, which forms the chimney proper.

b and *b'* show the double S clasp and joint-plate.

c shows the compression rings at the top and bottom of the chimney.

I usually (in making these chimneys) have a former made round, oval, or other desired shape, and have the rings *c* made to correspond in shape thereto. I then bend the mica around said former and secure the edges of the mica between the laps of the double S clasp *b*, or I place the joint-plate *b'* over the joint of the mica and secure them together by the upper and lower outer rings, *c*. I then remove the chimney from the former and crowd the upper and lower rings closely to their places on the inside. By this mode of manufacture it will be apparent that a good and useful article is produced.

I believe I have thus shown the nature, construction, and the advantage to be derived from the use of this improvement clearly enough to enable a person skilled in the art to make the same.

What I claim as new and of my own invention, as a new and improved article of manufacture, is—

A mica chimney for lamps, &c., the combination of mica *a*, form compression rings *c*, and a lateral joint-bar, *b'*, or double-S clasp *b*, substantially in the manner as and for the purpose described.

In witness whereof I have hereunto set my hand this 24th day of March, 1862.

EDWIN S. GAYLORD.
